FOLDING BOAT SEAT WITH ADJUSTABLE BACK REST

Joseph E. McDonald, Orr, Minn.

Application January 11, 1950, Serial No. 137,989

4 Claims. (Cl. 155—133)

1

This invention relates to portable folding seats particularly adapted for use on flat seats of row boats or boats using outboard motors, and in particular the invention relates to a seat structure having spring clips on the lower surface with a back pivotally mounted on the seat adapted to fold to a position parallel with the seat and also adapted to be supported in inclined positions for providing a back rest.

The purpose of this invention is to provide a folding seat particularly adapted for fishermen that may be carried to a boat and readily positioned on a seat thereof with the back opened to a comfortable position for providing a back rest.

Various types of adjustable backs have been provided in seat structures but where the back is carried by the seat the mounting means therefor are either heavy or do not permit the back to nest against the surface of the seat. With this thought in mind this invention contemplates a pair of unique hinge elements for pivotally mounting the back on a seat wherein the back may be suspended in adjusted positions on a pair of cams actuated by a crank at one side of the seat and locked by a gear and ratchet pin.

The object of this invention is, therefore, to provide means for hinging a back to a seat whereby the back is positively held in adjusted positions by cams journaled in the seat.

Another object of the invention is to provide a back supporting structure in a seat whereby the back is positively held in different positions and also adapted to fold upon a seat in which the structure may be used with seats of different types and designs.

A further object of the invention is to provide a seat structure with an adjustable back wherein the back is positively held in adjusted positions, which is of a simple and economical construction.

With these and other objects and advantages in view the invention embodies a seat having a rectangular shaped frame with spring clips on the lower surfaces of side bars thereof, a pair of brackets mounted on the inner surfaces of the side bars and having upwardly extended ends, a back pivotally mounted in the upwardly extended ends of the brackets on a shaft journaled in the side bars of the seat and having a crank on one end, a gear on the other end of the shaft positioned to engage a pin extended from the adjacent side bar, and cams positioned to engage the lower ends of the sides of the back.

Other features and advantages of the invention will appear from the following description taken in connection with the drawings, wherein:

2

Figure 1 is a side elevational view of the seat illustrating the seat positioned on a seat of a boat with the seat of the boat shown in section.

Figure 2 is a plan view of the seat with the back positioned as shown in Figure 1.

Figure 3 is a cross section through the seat taken on line 3—3 of Figure 2.

Figure 4 is a similar section showing the seat with the back folded upon the upper surface of the seat.

Figure 5 is a vertical section through the seat taken on line 5—5 of Figure 2.

Figure 6 is a detail showing one of the brackets for pivotally mounting the back upon the seat.

Referring now to the drawings, wherein, like reference characters denote corresponding parts the portable folding boat seat of this invention includes a seat panel 10, a back panel 11, brackets 12 and 13, a shaft 14 having a crank 15 on one end and a gear 16 on the other and cams 17 and 18 on the intermediate part of the shaft.

The seat 10 is formed with a frame having a front bar 19 with side bars 20 and 21 and spring clips 22 and 23 are mounted on the lower surfaces of the side bars by screws 24. The springs 22 and 23 hold the seat on a seat 25 of a row boat or outboard motor boat or the like so that the seat may be carried to the boat by the fishermen, mounted on the seat of the boat by the spring clips for use, and readily removed after use.

The back 11 is provided with a frame having an end bar 26 with side bars 27 and 28 and, as illustrated in Figure 3 the back is pivotally mounted by pins 29 and 30 in openings 31 in upwardly extended ends 32 of the brackets 12 and 13. The brackets 12 and 13 are similar and the same reference numerals are used for the openings and parts of both brackets. The brackets are secured to the inner surfaces of the side bars 20 and 21 of the seat by screws 33 in openings 34 and 35 and the brackets are also provided with openings 36 in which the shaft 14 is journaled.

The lower end of the back extends through the side bars of the seat, as illustrated in Figure 3 and the lower ends of the bars 27 and 28 of the back are connected by a cross bar 37. The cams 17 and 18 are positioned to engage the surfaces of the side bars 27 and 28, and the gear 16 is positioned to engage a ratchet pin 38. With the parts positioned in this manner the shaft 14 is moved inwardly by the crank 15 until the gear 16 disengages the pin 38 and at this time the cams may be turned by the shaft and crank to adjust the position of the back and when the back is in the proper position the crank 55 is released whereby the spring 39 actuates the

surfaces of the side bars 27 and 28, and the gear 16 is positioned to engage a ratchet pin 38. With the parts positioned in this manner the shaft 14 is moved inwardly by the crank 15 until the gear 16 disengages the pin 38 and at this time the cams may be turned by the shaft and crank to adjust the position of the back and when the back is in the proper position the crank 55 is released whereby the spring 39 actuates the

crank outwardly, bringing the gear 16 into engagement with the pin 38 so that the cams are locked in the position of retaining the back in the adjusted position.

By this means the back may readily be folded to a position upon the seat, as illustrated in Figure 4, for transporting the seat and when the seat is in position on the seat of a boat the back is raised and adjusted to a comfortable position by the crank through the cams.

The seat panels are shown as rabbeted in the end and side bars of the frames and the inner edge of the seat panel 10 is held by a cross bar 40 spaced from the ends of the side bars 20 and 21.

It will be understood that modifications may be made in the design and arrangement of the parts without departing from the spirit of the invention.

What is claimed is:

1. A seat having spring clips on the lower surface, a back pivotally mounted in the seat and positioned to extend upwardly and also to fold to a position upon and parallel to the seat, a shaft journaled in the seat, cams on the shaft positioned to engage the face of the lower end of the back, a ratchet on one end of the shaft for retaining the cams in adjusted positions, and a crank on one end of the shaft.

2. A seat having spring clips on the lower surface, a back pivotally mounted in the seat and positioned to extend upwardly and also to fold to a position upon and parallel to the seat, a shaft journaled in the seat, cams on the shaft positioned to engage the face of the lower end of the back, a ratchet on one end of the shaft for retaining the cams in adjusted positions, a crank on one end of the shaft, and a spring on the shaft

for urging the ratchet elements in locking relation.

3. A seat having a horizontally disposed panel with front and side bars, brackets with upwardly extended rear ends mounted on the rear ends of the side bars of the seat, a back pivotally mounted in the upwardly extended ends of the brackets, a shaft extended through the seat and journaled in the brackets, cams on the shaft positioned to engage the face of the back, a gear on the shaft positioned to coact with a pin on the seat for locking the shaft with the cams in adjusted positions, a crank on one end of the shaft, and a spring for urging the shaft with the gear in engagement with the pin.

4. A seat having a horizontally disposed panel with front and side bars, brackets with upwardly extended rear ends mounted on the rear ends of the side bars of the seat, a back pivotally mounted in the upwardly extended ends of the brackets, a shaft extended through the seat and journaled in the brackets, cams on the shaft positioned to engage the face of the back, a gear on the shaft positioned to coact with a pin on the seat for locking the shaft with the cams in adjusted positions, a crank on one end of the shaft, a spring for urging the shaft with the gear in engagement with the pin, and spring clips on the lower surfaces of the side bars of the seat for retaining the seat on a seat of a boat.
